UNITED STATES PATENT OFFICE.

JOHN L. GUERRANT, OF SEDALIA, MISSOURI.

FREIGHT-CAR DOOR.

Application filed May 25, 1920. Serial No. 384,147.

To all whom it may concern:

Be it known that I, JOHN L. GUERRANT, a citizen of the United States, residing at Sedalia, in the county of Pettis and State of

- 5 Missouri, have invented certain new and useful Improvements in Freight-Car Doors, of which the following is a specification, reference being had therein to the accompanying drawing.
- 10 This invention relates to grain car doors especially, although the improvements can be used on the doors of freight cars generally, it being the object of the invention to equip a freight car door with auxiliary doors
- 15 to facilitate filling the car with grain or other similar material, and for discharging the grain or giving access to the contents behind the car door, so that the car can be emptied conveniently, such auxiliary doors
- 20 being of novel construction to enhance the utility and efficiency thereof.

Another object is the provision of novel means for mounting the auxiliary doors from the main car door, so as to provide a

25 practical and serviceable construction.

A further object is the provision of novel means whereby the main door as well as the auxiliary doors can be retained in closed position under a single seal, preventing either the main door or auxiliary doors being opened without breaking the seal, and the device being comparatively simple in construction and operation as well as practical and reliable.

35 A still further object is the provision of novel means for fitting and clamping the main car door to the door frame, to provide a tight fit or joint for preventing the grain or other contents from leaking past the door, without the necessity of using an inner grain door as customary, and this feature is also useful for excluding dust, dirt, rain, air and the like, from the contents of the car.

With the foregoing and other objects in view, which will be apparent as the description proceeds, the invention resides in the construction and arrangement of parts hereinafter described and claimed, it being understood that changes can be made within

50 the scope of what is claimed, without departing from the spirit of the invention.

The invention is illustrated in the accompanying drawings, wherein:—

Figure 1 is a face view of the improved

55 door construction.

Figs. 2, 3, 4, 5, 6, 7, and 8 are sectional details taken on the respective section lines 2—2, 3—3, 4—4, 5—5, 6—6, 7—7, and 8—8 of Fig. 1.

Fig. 9 is a face view of a modified form of auxiliary door.

Fig. 10 is a fragmentary face view illustrating another mode of mounting the auxiliary doors.

The door frame comprises, as usual, the sill 14, and the posts 15 and 16 at the opposite sides of the door opening, and the main car door 17 as shown, is composed of two layers of wood, although it can be of metal, combination wood and metal or other suitable construction. The door is suspended for longitudinal movement along the exterior of the car wall from a suitable track 18' extending over the doorway or opening.

The door 17 and door frame are provided with means to fit them tightly together, when desired, for preventing leakage and also excluding the elements from the outside of the car. Thus, a horizontal metallic strip 18 is secured to the outer side of the door 17

70 along the lower edge thereof, and projects downwardly beyond said edge of the door, as seen in Fig. 8, and the lower edge portion of the strip 18 is bent back inwardly to form a hook or channel 19 which extends under

75 and behind a depending flange 20 offset outwardly from a plate or strip 21 secured to the outer side of the sill 14. The offset portion of the strip 21 extends below the door

80 17, when the door is closed, and when the door is moved to closed position, it moves over the flange 20, while the hook or channel 19 passes under and behind the flange 20.

Bolts 22 are inserted through apertures in the strip or plate 18 and the flange 20, for

85 clamping them together, and clamping the door 17 against the strip 21, thereby providing a tight joint or fit between the sill and lower edge portion of the door. Retaining

90 arms or brackets 23 are also preferably secured to the sill 14 below the strip 21 with their free ends extending upwardly in front of the strip 18 to hold the lower edge of the door 17 against the door frame and assisting

95 in guiding the door and retaining it in

100 proper place.

A vertical metallic strip or plate 24 is secured to the outer side of the door post 16 (see Fig. 6) and has a portion 25 bent outwardly at an angle to form a stop for the

105

110

2

door, against which the forward vertical side edge of the door 17 abuts when said door is slid to closed position. The portion 25 has a flange 26 bent at an angle away from the door, and a vertical strip 27 is secured to the outer side of the door along the corresponding vertical edge thereof and projects beyond the edge of the door to overlap the flange 26 when the door is closed. 10 Bolts 28 are inserted through apertures in the strip 27 and flange 26 for clamping them together, when a tight joint is desired. A vertical strip 29 secured along said edge of the door at the inner side thereof, also projects beyond said edge to enter a vertical groove 30 provided between the strip 24 and post 16, thereby providing a more perfect joint against leakage.

A vertical strip 31 composed of two parts 20 is secured to the opposite vertical edge of the door, and is provided beyond the inner side of the door, with flanges 32 and 33 bent at an angle and projecting in opposite directions. A vertical strip or plate 34 is secured to the outer side of the door post 15, and that edge portion of the plate 34 nearest the doorway is bent back outwardly, as at 35, to provide a channel or groove for receiving the flange 33, when the door 17 is in closed position, thereby providing a tight joint, similar to that formed by the projecting portion of the strip 29 fitting in the groove 30, as above described. The flange 32 is used for clamping the corresponding edge portion of the door to the door frame, bolts 36 being inserted through apertures in the flange 32 and strip 34, and taking into the nuts 37 embedded in the post 15 behind the strip 34.

40 Coming to the auxiliary doors, the main door 17 is provided with openings 38 therein near the upper and lower edges thereof and near that vertical edge of the door 17 which moves across the doorway in opening 45 and closing the door. Metallic frames 39 and 40 surround the openings 38 at the inner and outer sides of the door, respectively, and are secured to the door to reinforce it at the openings 38. Each outer frame 40, 50 which comprises a flat plate, is provided at that edge nearest the opening 38 with an outturned portion 41 surrounding the opening, and having a flange 42 extending at an angle away from the opening, to receive the auxiliary door.

The upper and lower auxiliary doors are designated 43 and 44, respectively, and, as shown, they are duplicate constructions in reversed positions. Each auxiliary door comprises a rectangular cap 45 of sheet metal or other suitable material, having the marginal rim or flange 46 to surround the flange 42 and portion 41 when the cap is fitted against the flange 42, as seen in Fig. 2. The 55 rim or flange 46 overlaps and is secured to

a rim member 47 of angular cross section, and said member provides a stiff marginal portion or rim for the door. The rim member 47 is adapted to fit snugly against the frame or plate 40, and can be secured firmly thereto by means of bolts 48 inserted through apertures in the member 47, frame 40 and door 17, to screw into nuts 49 embedded in the inner surface of the door behind the frames of plates 39.

70 In order to mount the auxiliary doors 43 and 44 for movement to and from the openings 38, hinged arms 50 are used, each of them having a U-shaped portion 51 extending across the outer side of the corresponding cap or panel 45, and the arms 50 of the upper and lower auxiliary doors are in reversed position, as seen in Fig. 1. The ends of the portions 51 have hinge butts 52 mounted on horizontal hinge rods 53 disposed above and below the upper and lower auxiliary doors, respectively. As shown, each rod 53 extends through lugs 54 of a plate 55 secured to the door 17, with the ends of the rod seated in lugs 56 of plates 57 secured to the door at the opposite ends of the plate 55, with the hinge butts 52 between the lugs 54 and 56. The portions 51 have the caps or panels 45 of the auxiliary doors secured thereto by means of bolts 58, or the like, whereby the auxiliary doors will swing with the arms 50. The arms 50 have the extensions 59 projecting from the portions 51, which are offset to lie close to the door 17 when the auxiliary doors are closed, and bolts 60 are used, similar to the bolts 48, for fastening the extensions 59 to the door 17, said bolts 60 screwing into nuts 61 embedded in the door 17 similar to the nuts 49.

90 With the arrangement as shown, the extensions 59 of the two arms 50 project toward one another, and a hasp arm 62, similar in shape to the arms 50, is used for sealing all three doors 17, 43, and 44. The U-shaped portion 63 of the arm 62 has hinge butts 64 at its ends mounted on vertical hinge rods 65 seated in lugs 66 of plates 67 secured in pairs to the door 17, so that when the arms 50 have been swung to close the auxiliary doors, the arm 62 can be swung to bring the opposite members of the portion 63 across the extensions 59, as seen in Fig. 1. The arm 62 has a hasp 68 extended from the portion 63 and is provided with a slot 69, and the arm 62 can be secured to the door 17 similar to the arms 50, by means of a bolt 70 which takes into a nut 71 embedded in the door 17, as seen in Fig. 3.

100 A latch is used for holding the arm 62 and retaining it in position under a single seal for all three doors. For this purpose, a plate 72 is secured to the strip or plate 24, and has outstanding keepers 73 and 74 so arranged that the hasp 68 passes over the keeper 73 when the arm 62 is swung to latch-

ing position. The keepers 73 and 74 have openings 76 for receiving the latch 75 to retain the arm 62 in place under the seal. The latch 75 is slidable vertically, as shown, and 5 is movable between vertical guides 77 offset from a plate 78 secured to the plate 72, said latch having flanges 79 movable behind said guides to retain the latch for vertical movement to and from latching position. Thus, 10 when the hasp 68 has been moved over the keeper 73, with the latch 75 in raised position within the guides 77, the latch can be dropped or slid downwardly through the keepers across the hasp 68, thereby preventing 15 the arm 62 from being swung away from the door frame to release the arms 50. In order to receive the seal, the latch 75 has an outstanding ear 80 near its upper end to move downwardly close to the keeper 74 20 when the latch is moved to latching position, and the ear 80 and keeper 74 have registering openings 81 to receive the seal 82, which prevents the latch being retracted upwardly, without breaking the seal. Consequently, 25 the arm 62 can not be released without breaking the seal and raising the latch, and this holds the door 17 under the seal, as well as the auxiliary doors, the arms 50 of which are held by the hasp arm 62. The arrangement 30 is simple and effective, the auxiliary door arms 50 engaging a third arm which is held by the latch and seal.

In using the door 17, such as when filling the car with grain, the door 17 is slid to 35 closed position, thereby bringing the hook or channel 19 under and behind the flange 20, and moving the strip 29 and flange 33 into the respective grooves or channels 30 and 35. The bolts 22, 28 and 36 are then 40 applied and tightened, to clamp the vertical and lower edges of the door 17 tightly to the door frame, to prevent leakage of grain, and to make the door 17 perfectly rigid and secure. The lower arm 50 is then swung upwardly to close the lower auxiliary door 44, and the bolts 48 are then applied to clamp 45 the door 44 against the corresponding frame 40, and the bolt 60 is also applied for holding the arm 50 firmly in place to resist the outward pressure against the panel or cap 45. The upper door 43 can be swung open by raising the upper arm 50, and the grain can then be run through the upper opening 55 38 for filling the car. After the car is filled, the upper auxiliary door 43 is closed, by swinging the arm 50 downwardly, and the upper auxiliary door can also be fastened by the bolts 48, and the upper arm 50 is fastened by the bolt 60. The arm 62 is then 60 swung across the extensions 59 and fastened by the bolt 70 and the hasp 68 then moved over the keeper 73. The latch 75 after being moved downwardly across the hasp 68 within the keepers 73 and 74, is fastened by the seal 82. The doors 17, 43 and

44 are thus maintained in closed position under a single seal, and neither of said doors can be opened without breaking the seal.

To start the discharge of grain from the car, the seal is broken and the latch 75 raised, and the bolt 70 then loosened thereby releasing the arm 62 so that it can be swung open away from the extensions 59 of the levers 50. The bolts 48 of the auxiliary door 44 are then removed, and when the bolt 60 is loosened, the lower auxiliary door will swing open downwardly, thereby starting the discharge of grain through the lower opening 38. The bolts 22, 28 and 36 can then be removed, for sliding the door 17 open, and if necessary, the upper auxiliary door 43 can be opened before moving the door 17, to give entrance into the car for clearing the grain from behind the door 17. The door 17 can then be slid open, so that a shovel can be 85 used for removing the grain, or enabling the grain to be removed in the customary way.

The door is also useful for other merchandise and the bolts 22, 28 and 36, need not be used, unless it is desired to hold the door 17 rigidly against the door frame, to resist the jamming or jostling of the merchandise against the door 17, or to prevent leakage of the contents from the car or the entrance of dirt, dust, rain, air or the like, 90 into the car, thus protecting the contents thereof. The single seal will hold all three doors closed, and by releasing the arms 62 and 50, the auxiliary doors can be opened for gaining access to the contents, without 100 opening the door 17, whereby merchandise in rear of the door 17 can be removed or loosened should the merchandise jam up against the door. In using the door for ordinary freight, the bolts 48 of the auxiliary doors need not be used, unless it is desired to hold the auxiliary doors tight against the frames 40 to prevent leakage. Any water or moisture which may leak past the upper edges of the auxiliary doors between the upper edges of the frames 40 and rim members 47, will be caught within the channels or troughs formed by the portions 41 and flanges 42 of the frames 40, thereby draining such water around the opposite sides of the openings 38, to drain downwardly past the lower edges of the auxiliary doors, without entering the openings 38.

The auxiliary doors when used with certain classes of freight, such as fruit, vegetables and the like, requiring ventilation or examination, can have the caps or panels 45 substituted by others, one of which is shown in Fig. 9. The cap or panel 45' replaces the cap or panel 45 and rim member 47, and is secured to the corresponding arm 50. Said panel or cap 45' has slots or openings 45^a, providing for ventilation, and also enabling an inspector to observe the contents without being able to remove same. The cap or

panel 45', as shown, eliminates the rim member 47, which is not necessary in this case.

In Fig. 10, a modified mounting for the lower auxiliary door is shown, permitting said door to swing upwardly, instead of downwardly, thereby avoiding the possible injury to the person opening such door, should there be any such liability with the downwardly swinging door 44, as above described. The lower auxiliary door 44' as shown in Fig. 10 is of the same construction as the door 44 above described, and the panel or cap 45 thereof is secured by means of bolts 48 or the like, to vertical hinge straps or arms 51' hingedly connected at their upper ends above the door 44' to the door 17, and a retaining arm 50' is hinged to the door 17 at its lower end below the door 44' and extends upwardly across the auxiliary door and behind the hasp arm 62, being secured to the door 17 by the bolt 60 as hereinbefore described in connection with the arm 50. The arms 50' and 51' are hinged to the door 17 by means of hinge rods 53' seated in lugs 56' secured to the door 17, similar to the hinges hereinbefore described. With this arrangement, when the arm 50' is released by the arm 62, the arm 50' will swing downwardly when the bolt 60 is loosened, but the auxiliary door 44' will swing upwardly in opening. The arm 50', however, retains the auxiliary door 44' in closed position when held by the arm 62, although the door 44' is hinged at its upper edge independent of the hinge of the arm 50', thereby separating the hinges of the door and retaining arm and locating them so that the door 44' can swing open outwardly and upwardly to avoid possible injury to the person releasing the arm 50'.

Having thus described the invention, what is claimed as new is:—

1. A freight car door having upper and lower openings, an auxiliary door for each of said openings, means for individually holding said auxiliary doors closed and engaging the car door, a single unit between said openings cooperable with the aforesaid means for holding both auxiliary doors closed, and means for the attachment of the last named means to the car door frame for holding all three doors closed.

2. A freight car door having upper and lower openings, auxiliary doors to extend across and close said openings, an arm for each auxiliary door hinged to the car door beyond one edge of the auxiliary door and extending across such auxiliary door with the free end of the arm projecting beyond the opposite edge of the auxiliary door, and means carried by the car door for overlapping and holding the free ends of said arms.

3. A freight car door having upper and lower openings, auxiliary doors to extend across and close said openings, arms hinged

to the car door beyond the opposite edges of the two auxiliary doors and extending across said doors toward one another with the free ends of said arms projecting beyond the adjacent edges of the auxiliary doors, and means carried by the car door between said openings for overlapping and holding the free ends of said arms.

4. A freight car door having two openings, auxiliary doors to extend across and close said openings, arms hinged to the car door beyond the opposite edges of the auxiliary doors and extending across said auxiliary doors toward one another with the free ends of said arms projecting beyond the adjacent edges of the auxiliary doors, and an arm hinged to the car door between said openings to swing toward the car door and overlap the free ends of said arms.

5. A freight car door having upper and lower openings, auxiliary doors to extend across and close said openings, an arm hinged to the car door below the lower edge of the lower auxiliary door and extending upwardly across said lower auxiliary door with its free end projecting above the upper edge of the lower auxiliary door, and means carried by the car door between the upper and lower openings for overlapping and holding the upper end of said arm and also arranged for holding the upper auxiliary door closed.

6. A freight car door having upper and lower openings, auxiliary doors to extend across and close said openings, an arm hinged to the car door at the lower edge of the lower auxiliary door and extending upwardly across said lower auxiliary door, and an arm hinged to the car door between said openings to swing toward the car door and overlap the upper end of the first named arm, the second named arm being also arranged to hold the upper auxiliary door closed.

7. A freight car door having an opening, a frame surrounding said opening having an outturned portion provided with a flange extending away from the opening and forming a trough surrounding the opening for catching moisture and water and conducting same around the opening, an auxiliary door including a cap to fit against said flange and to surround said portion, and retaining means for holding the auxiliary door in place.

8. A freight car door having an opening, a frame surrounding said opening having an outturned portion surrounding the opening, an auxiliary door having a cap to surround said portion and a rim member to bear against said frame, means for securing said rim member to the frame, and retaining means carried by the car door to extend across said cap.

9. A freight car door having upper and

lower openings, auxiliary doors to extend across and close said openings, means for holding said auxiliary doors closed including arms extending toward one another beyond the adjacent edges of the auxiliary doors, said arms being swingable away from one another and away from the car door for opening the auxiliary doors, and means carried by the car between said openings to

overlap the adjacent ends of said arms and hold them adjacent to the car door.

10. A freight car door having upper and lower openings, auxiliary doors to extend across and close said openings, means for holding said auxiliary doors closed including arms extending toward one another beyond the adjacent edges of the auxiliary doors, said arms being swingable away from one another and away from the car door for opening the auxiliary doors, and a third arm hinged to the car door between said openings to swing toward the car door and overlap the adjacent ends of the aforesaid arms.

25. 11. A freight car door having upper and lower openings, an auxiliary door to be disposed across each of said openings, members movable toward the car door for holding the auxiliary doors across said openings,

means for individually securing said members to the car door for holding the auxiliary doors closed, a member carried by the car door and movable toward said car door to engage the aforesaid members for holding them and the auxiliary doors in place, and means for fastening the last named member to the car door frame against movement away from the car door and to hold the car door closed.

12. A freight car door having upper and lower openings, an auxiliary door to extend across each of said openings, a member associated with each auxiliary door for retaining same in place across the corresponding opening, means for individually securing said members to the car door for holding the auxiliary doors closed, means carried by the car door between said openings and movable as a single unit to engage said members simultaneously for holding both auxiliary doors in place, and means for fastening the last named means to the car door frame to hold said last named means and car door.

In testimony whereof I hereunto affix my signature.

JOHN L. GUERRANT.
